UNITED STATES PATENT OFFICE.

VINCEN P. McVOY AND ROSWELL B. KING, OF PENSACOLA, FLORIDA.

MEANS FOR CALKING VESSELS.

No 853,723.

Specification of Letters Patent.

Patented May 14, 1907.

Application filed January 15, 1907. Serial No. 362,385.

To all whom it may concern:

Be it known that we, VINCEN P. McVOY and ROSWELL B. KING, of Pensacola, in the county of Escambia and State of Florida, have invented certain new and useful Improvements in Means for Calking Vessels; and we do hereby declare the following to be a full, clear, and exact description of the invention, such as will enable others skilled in the art to which it appertains to make and use the same.

This invention relates to means for protecting the calking in the seams of wooden vessels and to prevent it from working out.

The primary object of this invention is to provide for this purpose a metallic strip of such formation that it will fit snugly into an ordinary seam without overlapping the edges thereof, and which may be readily bent to conform to all curves in the boat. And a further object is to provide means for securing the strip in such a manner that both it and the fastening means will be flush with the planking.

The invention will be hereinafter fully set forth and particularly pointed out in the claims.

In the accompanying drawings, Figure 1 is an elevation. Fig. 2 is an enlarged section on line 2—2, Fig. 1. Fig. 3 shows a slight modification. Fig. 4 is a sectional view on line 4—4, Fig. 3. Fig. 5 is an enlarged fragmentary view in perspective of the metallic strip.

Referring to the drawings, 1 designates a metallic strip, preferably of copper, of hemispheroidal shape in cross section, that is, it is formed with an outer flat face 2, and a convexed inner face 3. This strip is designed to fit in the seam 4, formed by the jointure of the planking, after the ordinary calking 5 has been inserted. It is preferably held in place by staples 6, as shown in Fig. 1, trans-

verse grooves 7 being formed at suitable distances in the flat face 2 to accommodate the heads of the staples so that they, as well as the flat face of the strip, will be flush with the planking. The staples also aid in holding the latter together. In lieu of staples, tacks 8, having heads projecting laterally at one side only, may be employed, the edges of the flat face of the strip being provided with countersunk recesses 9 for the accommodation of such heads. (See Figs. 3 and 4.)

The advantages of our invention are apparent. It will be seen that a strip of the form stated not only protects the calking, but also prevents barnacles and insects from entering the seams, and yet leaves no projecting surfaces beyond the planking. The hemi-spheroidal formation of the strip permits it to be readily bent, and does not necessitate the formation of any special form of seam.

We claim as our invention:

1. A device for protecting the calking in the seams of vessels, comprising a metallic strip having an outer flat face and an inner convexed face, said outer face having indentations therein, and fasteners fitted in said indentations.

2. A device for protecting the calking in the seams of vessels, comprising a metallic strip having an outer flat face and an inner convexed face, said outer face having indentations therein, and staples for fastening said strip fitting in said indentations.

In testimony whereof, we have signed this specification in the presence of two subscribing witnesses.

VINCEN P. McVOY.
ROSWELL B. KING.
